(57) **CLAIM**

The ornamental design for a packaging bottle for liquid personal care and home care products with dispensing pump, as shown and described.

DESCRIPTION

1. Packaging bottle for liquid personal care and home care products with dispensing pump

1.1 : Perspective

1.2 : Perspective

1.3 : Front

1.4 : Back

1.5 : Top

1.6 : Bottom

1.7 : Right

1.8 : Left

The design relates to a packaging bottle with dispensing pump for filling liquid personal care and home care products; the part represented by even broken lines forms no part of the claimed design; the dot-dash broken lines only show boundaries between the claimed-part and the disclaimed-part; 1.1. Bottom perspective view; 1.2. Top perspective view; 1.3. Front view; 1.4. Back view; 1.5. Top view; 1.6. Bottom view; 1.7. Right side view; 1.8. Left side view.

1 Claim, 8 Drawing Sheets
